DESIGN FOR A HAT

Adolph Reinsberg, Chicago, Ill.

Application December 14, 1942, Serial No. 109,031

Term of patent 3½ years

To all whom it may concern:

Be it known that I, Adolph Reinsberg, a citizen of the United States of America, residing in the city of Chicago, county of Cook, and State of Illinois, have invented a new, original, and ornamental Design for a Hat, of which the following is a specification, reference being had to the accompanying drawing, forming part thereof.

Fig. 1 is a front perspective view of a hat showing my new design.

Fig. 2 is a front perspective view showing the side opposite that shown in Fig. 1, and Fig. 3 is a front perspective view of the hat as shown in Figure 2 with the hood portion in turned down position.

Fig. 4 is a rear view of the hat shown in Fig. 1.
I claim:

The ornamental design for a hat, substantially as shown.

ADOLPH REINSBERG.
